UNITED STATES PATENT OFFICE.

OSCAR G. EDMOND, OF SPOKANE, WASHINGTON, ASSIGNOR OF ONE-HALF TO WHITE PINE SASH COMPANY, OF SPOKANE, WASHINGTON.

WOODWORKING MACHINE.

Application filed July 21, 1924. Serial No. 727,303.

To all whom it may concern:

Be it known that I, OSCAR G. EDMOND, a citizen of the United States, residing at Spokane, in Spokane County, and State of

Washington, have invented certain new and useful Improvements in Woodworking Machines, of which the following is a specification.

My present invention relates to improvements in woodworking machines adapted especially for boring and grooving the stiles of window sash for the accommodation of the sash cord. While the invention is applicable for use in machines adapted for other purposes, for convenience of illustration and description, I have confined the illustrations and description to the treatment of stiles of window sash. The machine is adapted to automatically and successively feed stiles from beneath a stack, step by step across a horizontal table, and during this lateral intermittent movement of a stile it is first bored by two spaced bits to form angular pockets; second a pair of rotary cutters form a groove extending between these two pockets; and third an invisible or secret pocket is bored in the stile at right angles to the first bores. In addition to the lateral movement of the stiles, they are moved longitudinally by mechanism for the purpose while being grooved. After the secret pocket is bored the finished stile is pushed longitudinally and delivered from the machine. The mechanism for performing the three operations are automatically actuated from a power shaft, and the feed and delivery of the stile which are also actuated from the power shaft, are properly timed in order that the stile may be automatically moved and operated upon from the time it is placed manually in a stack and delivered from the machine.

In the accompanying drawings I have illustrated one complete example of the physical embodiment of my invention wherein the parts are combined and arranged according to the best mode I have thus far devised for the practical application of the principles of my invention.

Figure 1 is a top plan view of a machine embodying my invention.

Figure 2 is a vertical longitudinal sectional view at line 2—2 of Figure 1.

Figure 3 is a view partly in end elevation showing a stack of stiles and a horizontal row of stiles; the feed mechanism, and indicating also the relative arrangement of the woodworking tools of the machine.

Figure 4 is a view in elevation at the operator's side of the machine, looking at the near side of Fig. 1.

Figure 5 is an enlarged detail view showing the actuating mechanism for the pusher feed for the stiles, and the controlling clutch mechanism.

Figure 6 is a view in elevation showing the opposite side of the machine from that of Fig. 4.

Figure 7 is a plan view showing the chain conveyor for moving the stile longitudinally and the discharge or delivery device.

Figure 8 is an enlarged detail view of a safety device in the pusher feed actuating mechanism.

Figure 9 is an enlarged view illustrating a boring bit and its operating mechanism, showing the machine frame in section.

Figure 10 is an enlarged detail view of the pusher feed device, showing its relation to the hopper in which the stack is formed.

The machine is provided with a frame or base 1 forming a housing for part of the operating mechanism, and a table or top 2 is provided for the machine. The power shaft 3 is provided with a pulley 4 and the belt, 5 in Figure 6 receives power from a suitable source for rotating the shaft and operating the machine.

The stiles or side bars of a window sash, which have been previously mortised and tenoned, are fed or supplied manually, to the machine, and in this supply a right side stile S is followed by a left stile S' in order that when the finished stiles are delivered from the machine, they may readily be arranged in pairs for assembling in the sash, shipping, or storing.

On the table top a feed hopper is arranged

2
to receive the stiles in a vertical stack, and from this stack the stiles are successively and intermittently pushed laterally into position for the three operations of the 5 woodworking tools. The lowermost or bottom stile of the stack is pushed from beneath it and a row of stiles is constantly being fed laterally of the table top.

The hopper or stack holder comprises a 10 pair of spaced, upright guide straps 6 and a laterally adjustable, elevated guide plate 7 having a lower horizontal flange 8 for the stiles. An end guide arm 9 (Fig. 4) together with the spaced uprights 6 and 15 plate 7 form a vertical hopper or trough for gravity feed of the stack of stiles.

The bottom stile of the stack is pushed laterally across the table by means of a laterally reciprocable, intermittently moving 20 pusher feed bar 10, which is disposed longitudinally of the top 2 of the machine, to successively feed the stiles to the right in Figs. 3 and 10. This push bar is operated by movement from a pair of spaced rock 25 arms 11 on the longitudinal rock shaft 12 which is journaled in bearings 13 at one side of the machine. At their upper ends these rack bars or arms 11 are provided with pivot bolts 14 to carry the angle brackets 15 30 which brackets are movable transversely of the machine in slots 16 of the table top. The brackets are coupled by bolts 17 to the push bar in order that the angle of the push bar may be adjusted to compensate for any 35 irregularities and to insure feeding the stiles in correct position to the woodworking tools of the machine.

The rock shaft 12 as seen in Figs. 4 and 5 is actuated from a cam shaft 18, which latter shaft is provided with gears as 19 that 40 engages a pinion 20 on the countershaft 21, the pinion being of sufficient length to permit relative movement while in engagement of the gear 19. On the countershaft 21 is a 45 pulley 22 over which a belt 23 passes from a pulley 24 on the power shaft 3 (Figs. 2 and 6). The gear wheel 19 is loose on the cam shaft 18, and the connection between the countershaft and the cam shaft is controlled by a clutch device comprising the 50 slidable clutch member 19' and the member 20' fixed on the cam shaft. A clutch lever 22' which extends to the operator's side of the machine for ready access is used to control the clutch and throw the cam shaft in or out of commission.

The oscillating movement of the arms 11 and consequent reciprocating movement of the pusher bar 10 are accomplished by a 60 flanged cam wheel 25 on the cam shaft 18, which wheel has a recess or depression 26 in the edge of its annular flange. A cam lever 27 having at its free end a roller 28 engaging the annular flange or cam wheel 25 is 65 loosely journaled on the rock shaft 12, but

is held thereto by resilient means for co-action with the shaft under normal operative conditions. A large spring 29 attached to the machine frame bears against the cam lever to constantly hold the roller of the 70 lever in contact with the cam wheel. As best seen in Fig. 8 the rock shaft 12 has a collar 30 adjoining the loose hub 27' of the lever 27, and this collar is fixed on the shaft by means of screws or set bolts 31. In opposite faces of its periphery the collar is fashioned with a pair of notches 32 in which the upper bent ends or hooks 33 of opposed complementary spring arms 34 engage. These spring arms are located at opposite 75 sides of the lever 27 and their lower ends are secured to the lever at 35. A double spring 36 having one pair of ends connected by a bolt 37 is disposed above the collar, and the lower free ends of this double spring engage the hooks or bent ends 33 of the 80 spring arms 34. From this arrangement of parts it will be apparent that with each single revolution of the cam wheel the spring 29 will swing the lever 27 forcing its 85 roller into the depression or recess 36 of the cam. The swinging movement of the lever, through the spring arms and notched collar, rocks the shaft 12 and through the oscillatable arms 11 the push bar is reciprocated. 90 At each reciprocation of the push bar the bottom stile is pushed from beneath the stack and the horizontal row of stiles on the table is moved the width of a stile, laterally across the table top.

This resilient driving connection between the cam lever and the rock shaft is provided for the purpose of stopping the reciprocation of the push bar in case of an emergency or accident, of improper feed of the stiles, or jamming of the push bar. In such instance the movement of the loose lever on the immovable rock shaft will cause disengagement and removal of the spring arms 34 from the notches in the collar. Upon 105 such removal of the spring arms the lever is free to swing on the shaft 12 without imparting movement thereto while the push bar is idle. The shaft and lever can again be restored to normal position for continued 110 operation of the feed mechanism and woodworking tools.

For the first operation of the woodworking tools on the first stile pushed from beneath the stack the stile is retained in position under the flange 8 of the plate 7 of the stacker or hopper, and two spaced, inclined holes are bored into the stile from the underside thereof by means of two boring bits 38 and 39. These boring bits are normally located under the table top 2 and are adapted to be projected upwardly through the top of the table to operative position for boring the holes, after which they are retracted or moved downwardly. These 115 120 125 130

bits bore a pair of spaced holes into the stile from the bottom or lower face thereof, and the parallel holes are inclined or slanted as indicated by the position of the bits in Fig. 4.

The boring bits are supported by a vertically arranged plate 40 mounted against the outer side of the machine frame on two bolts 41 and 42, and provided with arcuate 10 slots or slotted lugs 43 for the bolts. The lower end of the plate has a circular opening 44 therethrough which encases a complementary circular boss 45 on the side of the machine. Thus by first loosening the bolts 15 41 and 42 the plate may be swung within the limits of the slotted lugs 43 on the boss 45 to adjust the position of the boring bits with relation to the stile, and then the plate may be locked in adjusted position by turning home the bolts in their slots.

The operating shafts 46 and 47 of the boring bits are journaled to slide in bearings 40 of the plate 40 and the shafts are geared together at 48. Power is applied to pinion 25 49, through which shaft 47 may slide, by a bevel gear 50 on the power shaft 3, which shaft is journaled in the center of the circular boss 45 of the machine frame.

A carriage 51 is used as a means for alternately elevating the bits and their shafts to operative position, and for lowering them to inoperative position, and this carriage is reciprocated from the cam shaft 18 as follows: A cam 52 on said cam shaft (Figs. 35 4 and 5) has resting thereon a horizontally disposed cam lever 53 with a roller 54 and a pivotal end 55 supported on the machine frame. The other end of this cam lever is slotted at 56 for bolt connection to the carriage 51, and it will be apparent that with each revolution of the cam wheel 52 the lever 53 will be oscillated on its pivot 55 to lift and retract the carriage and its boring bits. As the carriage is elevated the 40 boring bits are projected and bore the two holes in the stile from the underside thereof, and after penetrating the stile the required distance the bits are withdrawn therefrom.

50 The bored stile is now moved laterally the width of a stile to the second position in Fig. 3 over the two aligned rotary cutter heads 57 and 58, which cutter heads or cutters form a longitudinal groove in the lower face of the stile terminating with the previously bored holes. The stile is grooved while it is being moved longitudinally to the right in Figs. 4 and 7 and the rotary cutter heads are operated while in relatively 55 stationary position. These rotary cutters are mounted on complementary shafts 59 and 60 journaled in a carrier plate 61 located below the table top and within the machine frame. The plate is pivoted on a horizontal 60 cross rod or bar 62, and has an angular

lever arm 63 depending therefrom. The lower end of this lever arm carries a roller 64 which co-acts with a cam 65 on the cam shaft 18. With each revolution of the cam shaft the carrier plate 61 is oscillated on its pivot 62 to reciprocate the rotary cutter heads 57 and 58, lifting them to operative position, and then lowering them to inoperative position.

These rotary cutters, for grooving the stile are operated from the power shaft 3 through a drive pulley 66 thereon and belt 67. The belt passes over pulleys 68 and 69 on the respective shafts 59 and 60, thence under an idle pulley 70. The pulley 70 is journaled on the free end of a horizontally disposed journal arm 71 pivoted at 72 within the machine frame, and provided with a weight 73. When the rotary cutters are in lowered, inoperative position, the gravity controlled arm 71 and its pulley are also in lowered position as in full lines Fig. 2, and the drive belt for the cutter heads is loose. As the carrier plate 61 is elevated the pulley 70 is also elevated, through the medium of the belt 67 which is looped under the pulley, to dotted line position in said figure. The weight of the pulley and its weighted arm 71 is sufficient to insure frictional engagement of the belt with the pulley to operate the pulleys 68 and 69 and thus rotate the cutter heads and groove the stile.

During the grooving operation the stile is being moved longitudinally to assist in the formation of the groove. As seen best in Figure 7 an endless conveyer chain 74 is mounted on the spaced sprocket wheels 75 and 76 above the table top. This chain carries a pair of spaced, laterally projecting pins 77 and 78, one of which engages the rear end of alternating stiles and moves the stile to the right in Figure 7 while the cutter heads are operating. After the grooving operation the other pin as 78 engages the same end of the stile and moves it further to the right to dotted position, but not however until after a third operation of the woodworking tools to be described.

The sprocket wheels for the conveyer chain in Fig. 7 have shafts 79 and 80 journaled in bearings 81 elevated above the table top, and the shaft 80 is provided at one end with a sprocket wheel 82 over which the drive chain 83 passes. This chain is driven from sprocket wheel 84 on the cam shaft 18 (Figs. 5 and 6).

During the grooving operation of the stile and while it is being shoved by one of the pins, as 77, the stile is retained in sliding position and prevented from rising from the table top by means of a presser foot or plate 85 which is actuated by the movement of the carrier plate 61 to bear down upon

the top surface of the moving stile while it is being grooved by the cutters. The presser plate is pivotally suspended from the free end of an arm 86 which extends longitudinally of the machine and is pivoted at 87 in an adjustable pivot plate 88 supported for slideable adjustment between vertical guides 89 on the vertically arranged elevated, retaining guide plate 90.

10 One end of the arm 86 is connected by bolt 91 to a horizontal link 92 pivoted at 93 at the opposite side of the plate 90, and a vertical link 94 connects this horizontal link with the carrier plate 61. Thus when 15 the carrier plate 61 is elevated to bring its cutters 57 and 58 into operative position, the presser plate is also moved to bear down upon the stile and hold it down as it moves longitudinally.

20 The slideable, adjustable, pivot plate 88 may be vertically adjusted by means of a screw 95 anchored in a bearing lug 96 on the plate 90 and passing through a nut 96' on the slide plate.

25 The retaining plate 90 flexibly supports the plate 90 by pivoted links 97.

As the stile is being grooved it is moved longitudinally toward the delivery end of the machine by the pins of the chain conveyor, and after the rotary cutters have been withdrawn the stile is again moved laterally by a reciprocation of the push bar which moves the horizontal row of stiles the distance equal to the width of one stile. The 30 stile is thus moved to position for operation thereon by the boring bit 98 which bores the invisible or secret pocket or hole in the stile from its lower face at one end of the groove. The pocket bored by the bit 98 is on an incline and the bit moves on its longitudinal axis at approximately right angles to the axial movement of the two bits 38 and 39. The shaft 99 of the bit 98 is longitudinally reciprocable in its journal bearings 100 which are located at the operator's side of the machine, and the bevel gear 101 is keyed on the shaft to permit this movement. The gear 101 and shaft 99 are revolved by complementary bevel gear 102 40 on a cross shaft 103 which shaft has a pulley 104 connected by belt 105 to the pulley 106 on the power shaft 3, for transmission of power to the bit. The bit shaft 99 is revolved by cam shaft 18 45 through the instrumentality of a cam wheel 107 on the cam shaft.

Against the cam wheel a cam arm 108 is held by a spring 109, the latter being secured 50 to the machine frame at one end and positioned to bear against the cam arm at all times. At one end the cam arm 108 is provided with a collar 110 on the bit shaft and is arranged in such manner that each rotation of the cam wheel 107 will cause a recip-

rocation of the bit shaft—the forward longitudinal movement of the shaft causing the revolving bit to bore into the stile to form the pocket or invisible hole, and the rearward movement of the shaft on its longitudinal axis withdrawing the bit from the bored pocket.

During the boring operation for the pocket the stile is held stationary by the foot plate 85, and after the pocket has been 70 bored the stile is ready to be moved longitudinally and delivered from the table top. For this purpose I employ a rotary member or disk 111 which is provided with a laterally projecting push pin 112 revolving about 80 the axis of the disk. The disk and pin are so arranged that at each revolution of the disk the pin will encounter or contact with the rear end of the finished stile, as indicated in Fig. 7, and "kick" the stile from the 85 table top.

The disk is fixed at the end of a horizontal cross shaft 113 and projects upwardly through a slot 114 in the table top. The shaft 113 is provided with a sprocket wheel 90 116 driven by the sprocket chain 83 which passes around a guide sprocket wheel 117 on the shaft 118, and the wheel 82 on shaft 80.

The horizontal row of stiles are thus fed, intermittently and successively across the 95 table top and operated upon in three different positions, and all parts of the machine are so related and timed that the several functions are performed in the proper order until the finished stile is 100 finally delivered at the end of the machine.

Having thus fully described my invention what I claim as new and desire to secure by Letters Patent is—

1. In a feed mechanism the combination 105 with a rock shaft having a loose cam lever thereon and a fixed member on said shaft, of resilient means operatively connecting said lever and member, a cam for actuating the lever, and means for permitting a slip movement between the rock shaft and lever to free the lever from said member.

2. The combination with a rock shaft having a fixed member and a loose member thereon and resilient means for operatively connecting said members, means for actuating the loose member to rock said shaft, and means for permitting a slip movement to free the loose member from the fixed member.

3. The combination with a rock shaft having a notched collar fixed thereon and a cam lever loose thereon, of opposed spring arms carried by said cam lever and engaging the notched collar whereby when the rock shaft is held against movement a slip movement of the spring arms from the notched collar is accomplished.

4. The combination with a rock shaft having a notched collar fixed thereon and a 130

- lever loose thereon, a cam and means for holding said lever in engagement with the cam, and a spring arm carried by said lever having engagement with the notched collar.
5. The combination with a rock shaft having a fixed notched collar and a cam lever loose on the shaft, of a spring for holding said lever in operative position, and a spring arm at each side of said lever for engagement with the notched collar.
- 10
6. In a pusher feed mechanism the combination with a rock shaft and a pair of spaced arms thereon, of a laterally reciprocable pusher bar, a pair of angle brackets pivoted on the free ends of said arms, and 15 an adjusting screw connecting each bracket to said push bar.

In testimony whereof I affix my signature.

OSCAR G. EDMOND.
